UNITED STATES PATENT OFFICE.

GUSTAV EGLOFF AND HARRY P. BENNER, OF INDEPENDENCE, KANSAS, ASSIGNORS TO
UNIVERSAL OIL PRODUCTS COMPANY, OF CHICAGO, ILLINOIS, A CORPORATION OF
SOUTH DAKOTA.

PROCESS FOR CRACKING PETROLEUM OIL.

Application filed August 20, 1920. Serial No. 404,896.

To all whom it may concern:

Be it known that we, GUSTAV EGLOFF and HARRY P. BENNER, citizens of the United States, and residing in the city of Independence, county of Montgomery, and State of Kansas, have invented certain new and useful Improvements in Processes for Cracking Petroleum Oil.

This invention relates to improvements in 10 process for cracking petroleum oil.

This invention relates to improvements in process for cracking petroleum oil, and refers more particularly to a process for cracking relatively heavy emulsified oils, as 15 for example, emulsified Mexican crudes, California crudes or bottom settling. Certain difficulties are experienced in the cracking of heavy emulsified oils, particularly that caused by foaming over of the contents 20 of the still, when the oil is heated in the still in the ordinary way. The oil in the bottom of the still becomes heated first, and this heavy asphaltic oil, acting more or less as an insulator, results in the upper portion 25 of the oil being heated slowly. The result is that before the upper portion of the oil has reached a vaporizing temperature, the water in the lower portion is explosively converted into steam, and in effect 30 lifts or throws the unconverted upper liquid portion out of the still, or, in other words, foams over.

The object of the present invention is to 35 overcome this difficulty, and further, to provide a novel and effective method of cracking these heavy emulsifying oils.

In the drawings, Fig. 1 is a view partly in 40 vertical section and partly side elevation of our apparatus. Fig. 2 is a transverse sectional view taken on lines A—A of Fig. 1.

Referring to the drawings, 1 designates the furnace provided with burner 2, grate 3, heating tubes or flue tubes 4, which are connected to the stack 5. These heating 45 tubes 4 extend through the upper part of the cylindrical shell or still 6. This still 6 is provided with man hole plates 7 and liquid draw off 8, controlled by valve 9. The lower part of the still is insulated as shown 50 at 10. The oil is continuously or intermittently fed to the still 6 by means of charging line 11, and charging pump 12, connected to any suitable source of supply.

The pump 12 is provided with the usual valves 13 and 14 as shown. The arrangement is such that the liquid level of the oil is maintained substantially at the level of the heating tubes. The vapors pass out of the still through the vapor outlet 15, in which is interposed valve 16. The vapor outlet 15 connects to dephlegmator 17. The upper part of the latter is connected to the water condenser coil 18 through pipe 19, in which is interposed throttle valve 20. The condenser coil 18 in turn leads to the receiver 21, which receiver has liquid draw off pipe 22, provided with control valve 23 and gas outlet pipe 24, provided with control valve 25. It also has liquid level gauge 26 and pressure gauge 27. The reflux condensate passes out of the dephlegmator through line 28 to any suitable supply storage tank. This line is controlled by valve 29. In order to prevent the reflux condensate from falling back into pipe 15, the upper end of the latter is provided with a spaced cap member 30.

The process may be operated as follows:

The still may be charged to the level of the heating tubes with bottom settling of a mid-continent crude petroleum of 15.2 degrees Baumé gravity, containing 18% of water in an emulsified condition. This oil was a particularly difficult oil to crack even without its water content, and in fact had a very large carbon content. Moreover, this oil foamed badly in atmospheric distillation. The upper surface of the oil in the still was maintained at an oil temperature of about 720 deg. F. under a pressure to and through the condenser of about 60 pounds per square inch. The temperature at the top of the dephlegmator was about 400 deg. F. so that none of the steam condensed in the dephlegmator. The oil and water collected in the receiver and stratified by gravity. 45% of pressure distillate was obtained of 53 degrees Baumé gravity. This pressure distillate upon redistillation gave 27% of 58 degrees Baumé gravity gasoline on the basis of the bottom settling treated without the water content. In other words, 27% of the original oil content of the charge was converted into gasoline of the gravity given. It may also be noted that the reflux condensate which was collected was itself capable of

further cracking and was separately collected.

The above figures were obtained from actually carrying out the process herein described.

The process may be operated either as a batch or continuous process, and, if desired, differential pressure may be maintained in the system by regulating the valves 16, 20, 23 and 25. In other words, distillation might take place at 100 pounds pressure, dephlegmation 50 pounds to atmospheric pressure and final condensation at 25 pounds to atmospheric pressure.

We claim as our invention:

1. A process of cracking emulsified petroleum oils, consisting in vaporizing such oil under sufficient temperature and pressure to cause cracking of said oil, subjecting the oil to surface heating alone to prevent

undue foaming; removing and collecting and condensing the vapors, first subjecting said vapors to a reflux condensation and independently separating and collecting the reflux condensate.

25

2. The process of cracking emulsified petroleum oil, comprising subjecting the oil to surface heating alone to vaporize the same at a cracking temperature and pressure, in condensing and collecting the vapors produced.

30

3. The process of cracking emulsified petroleum oil, comprising subjecting the oil to a surface heating alone to vaporize the same at a cracking temperature and pressure, in condensing and collecting the vapors produced, and in independently separating and collecting the reflux condensate.
